(57) **CLAIM**

I claim the ornamental design for a mobile phone stand, as shown and described.

DESCRIPTION

FIG. 1 is a first perspective view of a mobile phone stand showing my new design;

FIG. 2 is a second perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is another front view of the mobile phone stand of FIG. 1 shown in an alternate configuration.

Broken lines are for the purpose of illustrating portions of the mobile phone stand that form no part of the claimed design.
